(57) **CLAIM**

I claim the ornamental design for a drawer pull, as shown and described.

DESCRIPTION

FIG. 1 is a front perspective view of a drawer pull, showing my new design;

FIG. 2 is a rear perspective view thereof;

FIG. 3 is a front elevational view thereof;

FIG. 4 is a rear elevational view thereof;

FIG. 5 is a left-side elevational view thereof, the right-side elevational view being a mirror image thereof; and,

FIG. 6 is a top plan view thereof, the bottom plan view being a mirror image thereof.

The broken lines showing a cabinet door in FIG. 1 and a fastening screw in FIG. 2 depict environmental matter and form no part of the claimed design.
